UNITED STATES PATENT OFFICE.

ALBERT ARTHUR MOLTELNO DURRANT AND OWEN WILLIAM JOSEPH WATSON, OF CHISWICK, LONDON, ENGLAND, ASSIGNEES TO THE LONDON GENERAL OMNIBUS COMPANY, LIMITED, OF WESTMINSTER, LONDON, ENGLAND, A BRITISH COMPANY.

MEANS FOR REGULATING THE SUPPLY OF COMBUSTIBLE MIXTURE TO INTERNAL-COMBUSTION ENGINES.

Application filed December 8, 1923. Serial No. 679,385.

To all whom it may concern:

Be it known that we, ALBERT ARTHUR MOLTELNO DURRANT, a subject of the King of England, and OWEN WILLIAM JOSEPH WATSON, a subject of the King of England, both residing at Chiswick, London, England, have invented certain new and useful Improvements in Means for Regulating the Supply of Combustible Mixture to Internal-Combustion Engines, of which the following is a specification.

This invention is for improvements in or relating to means for regulating the supply of combustible mixture to internal-combustion engines, and has for one of its objects to provide for greater efficiency in operation at varying engine compressions.

It is well known that by heating the air supply to the carburetor economical running of the engine at low compressions, i. e. when the throttle is only partly open, is obtainable, but as the engine compression increases, i. e. when the throttle approaches and reaches full opening, this higher temperature of the carbureted mixture becomes undesirable as it entails undesirable diminution in the quantity of mixture admitted to the cylinder. These considerations are taken care of according to the present invention.

An object of the invention is to control the supplies of cool and heated air, and in so controlling these supplies to the engine carburetor 20 as the engine compression increases the temperature of the air supply decreases. The apparatus for carrying out this method consists of a carburetor for the engine with means for supplying cool air thereto, means for supplying heated air thereto, and a regulating-device controlling both of said supplies to vary the relative proportions thereof and consequently the temperature of the air used by the carburetor. Thus it will be seen that for all degrees of engine compression it will be possible to work with the most suitable temperature of the combustible mixture.

It is a feature of the invention to provide for variable relative motion to occur be-

tween the main throttle and the device which controls the supplies of cool and heated air. For instance in some circumstances it will be preferred to arrange that the movement of the main throttle from closed position to some position intermediate its closed and fully opened positions (for example to its half-way position) is without any corresponding effective operation of the said regulating-device. In other words up to say the half-way position of the main throttle the supply of air would be entirely from the heated source and from thence to the full open position of the throttle the temperature of the air would be gradually decreased. Suitable multiplying gear may be incorporated in the connections between the regulating-device and the throttle to provide for this or any other state of affairs.

For a more complete understanding of the invention there will now be described, by way of example only and with reference to the accompanying drawings, several constructional forms of apparatus according to the invention. It is to be understood, however, that the invention is not restricted to the precise constructional details set forth.

In these drawings:

Figure 1 is a vertical section showing the main throttle of an engine with one form of regulating-device according to the invention applied thereto.

Figure 2 is a section on the line 2—2 of Figure 1.

Figure 3 is a sectional view showing a muff surrounding an engine exhaust pipe whereby a supply of heated air may be obtained for the carburetor.

Figure 4 is an elevation, partly in section on the line 4—4 of Figure 5, of another form of carburetor and regulating-device according to the invention, and

Figure 5 is a plan view of the parts shown in Figure 4.

Like reference numerals indicate like parts throughout the drawings.

It will be understood that the apparatus itself may take many different forms. It may constitute an attachment to an existing

carburetor or it may be embodied as a part of the carburetor itself.

In the construction shown in Figures 1 and 2, the carburetor jet is shown at 10 and 5 the main throttle of the engine at 44. The latter has a stem 45 extending from it by which it is operated and a spring 13 is provided which keeps the throttle head pressed against the part 14 of the casing in order to 10 prevent leakage.

Loosely mounted upon the stem 45 is an air-regulating valve 46 which is in the form of a rotary plug valve, like the throttle valve. The valve 46 carries a stud 47 to 15 which one end of a coiled spring 48 is attached the other end of this spring is anchored to a stationary part of the casing. The valve 46 also has formed upon it an abutment 49 two positions of which are shown in Figure 2. This abutment lies at the opposite side of the valve 46 to the side at which the spring 48 is mounted. Adjacent the abutment 49, and intended to co-operate therewith, is a pawl 50, two positions of which are also shown in Figure 2. The pawl 50 is pivoted at 51 in a stationary part of the casing and it will be seen that the pivot is situated nearer one end of the pawl than the other. The extreme end of 20 the longer part of the pawl is intended to bear against the abutment 49 and the spring 48 operates to keep these two parts in engagement with each other. The shorter part of the pawl 50 is intended to co-operate 25 with a cam 52 upon the stem 45. Two different positions are shown in Figure 2 for the cam 52. The casing includes a hot air supply conduit 53 and a cold air supply conduit 54, these conduits being controlled 30 by the valve 46. The hot air supply conduit may conveniently be connected to a pipe 19 (see Figure 3) leading from a muff 20 surrounding the engine exhaust pipe 21 or some other suitable conduit for heating 35 air as it follows the path indicated by the arrows 22 in Figure 3.

Referring to Figure 2, it will be seen that the valve 46 is shown open to the hot air conduit 53 and is completely closing the 50 cold air conduit 54. This corresponds to the closed position of the throttle as will be seen in Figure 1. The abutment 49, pawl 50 and cam 52 are shown in dotted lines in the position which they occupy with this 55 setting of the valves. As the throttle valve 44 is turned towards fully open position the point of the cam 52 moves, in a counter-clockwise direction as seen in Figure 2, until it makes contact with the short end of the 60 pawl 50. Until this occurs there will be no movement of the valve 46. Subsequently, however, the cam 52 will move the pawl 50 and cause the nose of the longer end thereof 65 to push the abutment 49 and turn the valve 46 against the control of the spring 48.

The two valves 44 and 46 will then move together, but not at the same rate because, owing to the situation of the pivot 51 of the pawl, the abutment 49 will be pushed around more quickly than the cam 52 pushes 70 the short end of the pawl. The arrangement provides a multiplying gear therefore in addition to the lost-motion at the commencement of the operation. Actually, in the construction illustrated, the throttle valve will be between one-third and one-half 75 open before the valve 46 will be operated and the change-over to full cool supply from full heated supply takes place during the remaining two-thirds or one-half of the 80 movement of the throttle valve.

Somewhat similar results are obtainable with the construction shown in Figures 4 and 5. In this construction a hot air conduit is shown at 55 and a cold air port at 56. 85 This conduit and port supply a chamber 57 leading to the carburetor jet. The conduit 55 and port 56 are controlled by a flap valve 58 pivoted at 59 and operated by a lever 60 also mounted upon the pivot 59 and controlled by a spring 61. The end of the lever 60 is chamfered off or otherwise suitably shaped at 62 to be operated by a rod 63 adjustably mounted in an arm 64 which is operated by the engine throttle valve 90 lever. It will be understood that by adjusting the setting of the rod 63 in the arm 64 the amount and time of travel imparted to the valve 58 can be adjusted while by suitably shaping the end 62 the rate of travel 95 can be varied as desired. The throttle valve lever may be in continuous connection with the arm 64 or may only engage the latter at some predetermined point in its travel, as 100 desired.

It is to be understood that the invention is not restricted to the precise constructional details hereinbefore set forth.

We claim:—

1. In an internal-combustion engine the combination with a carburetor of means for supplying cool air thereto, means for supplying heated air thereto, a regulating-device controlling both of said supplies to vary the relative proportions thereof and consequently the temperature of the air used by the carburetor, and connections between said regulating-device and the main throttle such connections comprising an arm moving with the throttle valve and a member movable with the regulating-device, the said member being shaped and disposed so as to afford a differential speed connection between the arm and regulating-device when it is engaged by the arm. 110

2. In an internal-combustion engine the combination with a carburetor of means for supplying cool air thereto, means for supplying heated air thereto, a regulating-device controlling both of said supplies to vary the 115 120 125 130

relative proportions thereof and consequently the temperature of the air used by the carburetor, and connections between said regulating-device and the main throttle such connections comprising an arm moving with the throttle valve and a lever having one long and one short arm whereof the latter

is adapted to be engaged by the arm on the throttle valve and the former engages the regulating-device. ¹⁰

In testimony whereof we have signed our names to this specification.

ALBERT ARTHUR MOLTENO DURRANT.
OWEN WILLIAM JOSEPH WATSON.
